HEEL GROOVING MACHINE

George T. Watt, Haverhill, Mass., assignor to
Pope Machinery Corporation, Haverhill, Mass.,
a corporation of Massachusetts

Application November 8, 1937, Serial No. 173,352

14 Claims. (Cl. 12—47.1)

This invention relates to machines for making wood heels and more specifically to machines for "grooving" or shaping the entire breast and shank lip surfaces of heel blanks for so-called Louis heels. This grooving operation is usually the first to be performed on the sawed-out heel blanks.

Expensive automatic grooving machines have been developed for doing this work, but it is an object of the present invention to provide a simple manually operable machine of comparatively low cost which will produce an equal quality of work at a favorable cost to the user.

The under side of the shank lip of a Louis heel is convexly curved to match the concave curvature of the subsequently formed heel seat so that a very slightly blunted arcuately curved edge is produced along the end of the shank lip of the finished heel. The various sizes of blanks in an ordinary factory order require correspondingly various radii of curvature at the under side of the shank lip so that a uniform lip thickness at the center may be maintained through all of the sizes and at the same time have the curved cut meet the turned surface subsequently made on the blank as determined by the size of the heel. It is another object of the present invention to provide a machine having means adjustable to obtain the desired shank curvature on heels of different sizes without affecting the center thickness of the shank lip.

Other objects of the invention will be apparent from the following description in conjunction with accompanying drawings, in which,

Fig. 1 is a side view of a machine embodying my invention;

Fig. 2 is a plan view of the same except that there is no blank clamped in the holder with the work holder rotated 90° in a clockwise direction and with the tool shown in its surface-of-revolution form;

Fig. 3 is an isometric view of the work holder seat plate and side support assembly;

Fig. 4 is a heel blank as it comes to the groover;

Fig. 5 is a similar blank after grooving; and

Fig. 6 is a partial side view showing work holder open to receive a heel blank.

The machine illustrated in the accompanying drawings comprises a frame 10 having a horizontal table 11 and spaced columns 12, 13 and 14 projecting upward from the table. A motor 15 is secured to the frame 10 beneath the table 11. A pulley 16 is fixed upon the armature shaft of the motor 15 and is operatively connected by a belt 17 with a pulley 18 fixed upon a horizon-

tally disposed spindle 19 mounted in bearings 20 secured on the table 11. A tool 21, which is shown in Fig. 2 in its surface-of-revolution form, comprises a pair of grooving cutters 22, Fig. 1, and a pair of lip trimming cutters 23. A heel blank discharge chute 24 is secured upon the table 11 by screws 25. A bracket 26 is mounted for horizontal adjustment upon the top of the table 11 and is normally held in its adjusted position by a bar 27 held against the bracket by a bolt 28 passing through the bar and engaging the table 11. A plate 29 carrying a heel breast stop 30 is adjustably mounted in vertically extending ways 31 in the bracket 26 and is held in its adjusted position by a bolt 32 passing through an elongated slot 33 in the bracket 26 and engaging the plate 29.

A horizontal plate 35 is supported for horizontal adjustment upon the top of the columns 12, 13 and 14 and is provided with aligned key ways 36 and 37 parallel to the axis of the spindle 19 and adapted to engage keys 38 and 39 fixed in the top of the columns 13 and 12 respectively. The plate 35 is held against the top surface of the columns 12 and 13 by brackets 40 secured to the columns by bolts 41. The plate 35 is held in its adjusted position by a bolt 42 passing through an elongated slot 43 in the plate 35 and engaging the column 14. An index pointer 44 projects from the edge of the plate 35 over a scale 45 upon the top of the column 14. The plate 35 is provided with a hollow vertically extending cylinder 46, the inner wall of which is provided with spaced annular recesses to receive bearings 47 which rotatably support a shaft 48. The shaft 48 is held against axial movement by a nut 49 threaded upon the shaft 48 and engaging the upper bearing 47. The shaft 48 is positioned so that its axis is perpendicular to the axis of the spindle 19. An offset bracket 50 is secured upon the lower end of the shaft 48 and adjustably supports a work holder beam 51. The beam 51 is held in its adjusted position by bolts 52 passing through slots 53 in the bracket 50 and engaging the beam 51. A spring 54 surrounds each of the bolts 52 with one end engaging the head of the bolt and the other end engaging the bracket 50. When the bolts 52 are slightly loosened, the springs 54 act to hold the parts together to exclude dirt but allow for relative sliding movement between the beam 51 and the bracket 50.

A heel blank holder is mounted upon the beam 51 and comprises a bracket 55 provided with a way 56 adapted to slidably engage a key 57 fixed upon the beam 51. The bracket 55 is normally 55

held in its adjusted position by bolt 58 passing through elongated slot 59 in the bracket 55 and engaging the beam 51. The bracket 55 (Fig. 2) is provided with dovetail ways adapted to slidably receive a dovetail slide 60 carried by a plate 61. The slide 60 is vertically adjustable in the ways by a collared screw 62 rotatably mounted in the slide 60 and engaging the bracket 55. The slide 60 is held in its adjusted position by a set screw 63 engaging the slide 60. A heel blank seat engaging plate 64 is mounted for adjustment in horizontally extending ways formed in the plate 61. The position of the plate 64 may be adjusted by a collared screw 65 rotatably mounted in a lug 15 projecting from the plate 61 and engaging the plate 64. The plate 64 normally is held in its adjusted position by a set screw 66 carried by the plate 61 and adapted to engage the plate 64. Extending perpendicular from the plate 64 is projection 69 having vertical ways for receiving for 20 slidable adjustment therein, a heel blank side support 67. The support 67 is held in its adjusted position by a screw 68 passing through an elongated slot (not shown) in the projection 25 69 and engaging the support 67. A lip support 70 is slidably mounted in dovetail ways 71 in the plate 64 the edge of which is adapted to be engaged by the bevelled edge of a plate 72 which is secured in position against the support 70 by a screw 73. The support 70 is formed of a material which may be engaged by the tool 21 without 30 injury thereto such, for example, as fibre or Babbitt metal. The surface of the support 70 is aligned with the heel seat engaging surface of the plate 64.

A heel blank top lift engaging jaw 80 is carried by a bracket 81 which is adjustably mounted upon the beam 51 and is held in its adjusted position by bolts 82 passing through slots 83 in the bracket 81 and engaging the beam 51. The jaw 89 is slidably mounted upon the bracket 81 between spaced guides 84 upon the latter and is held in sliding engagement with the bracket 81 by a bolt 85 passing through an elongated slot in the jaw 80 and engaging the bracket 81. A manually operable lever 86 is pivotally mounted upon a bolt 87 fixed upon the bracket 81. The inner end portion 88 of the lever 86 forms one link of a toggle and is pivotally connected to the other link 89 of the toggle by a pin 90. The toggle link 89 is pivotally connected to the jaw 80 by a pin 91 and comprises a yoke 92 carrying spaced bolts 93 which pass through and slidably engage one end of a member 94, the other end of which is pivotally connected to the pin 91. A spring 95 surrounds each of the bolts 93 with one end engaging the yoke 92 and the other end engaging the member 94. The downward movement of the lever 86 is limited by a stop 96.

A locking mechanism is provided for holding the heel blank holder in desired relation to the tool 21 while adjusting the position of the shaft 48 to change the radius of the arc through which the heel blank is moved past the tool 21. This mechanism comprises an arm 97 pivotally mounted upon a fixed bracket 98 to swing in a vertical plane into and out of its operative substantially horizontal position, the latter being determined by a stop screw 99. The free end portion 104 of the arm 97 serves as a clamp jaw adapted to engage a lug 100 projecting upward from the beam 51. A lever 101 is pivotally mounted upon a pin 102 carried by the arm 97 and is arranged to swing in a plane perpendicular to the plane of pivotal movement of the arm 97. The arm

103 of the lever 101 serves as a clamp jaw adapted to cooperate with the jaw 104 to engage the lug 100 and hold the work holder in a desired position in relation to the tool 21. The jaw 103 is moved toward and away from the jaw 104 by a screw 105 carried by the other end of the lever 101 and engaging the arm 97.

In Fig. 4 a wood heel blank B is shown having a top lift surface T parallel to and directly opposite the heel seat surface. The breast surface 10 G is the surface which is grooved by the machine of the invention to form the breast b of the heel (Fig. 5) and the convex shank s. The machine also smooths the lip L of the shank. It is customary in wood heel manufacture to maintain a uniform center thickness of lip, as indicated by the line C in Fig. 5 on all sizes of heels of a given style.

In the operation of the machine the heel blank holder is moved to a position over the breast stop 30 as shown in Figs. 1 and 3. The lever 86 is moved upward to the position shown in Fig. 6, and the heel seat and breast G of the blank B are placed in engagement with the plate 64 and stop 30 respectively and with the side of the blank engaging the support 67. The lever 86 is then moved downward in engagement with the stop 30 as shown in Fig. 1 to cause the jaw 80 to engage the top lift surface T of the heel blank and clamp the blank in the work holder. The work holder then is rotated about the axis of the shaft 48 to move the heel blank past and in operative relation to the tool 21 and return the work holder to its initial position. The lever 86 then is moved upward to the position shown in Fig. 6 to permit the grooved blank to drop by gravity into the discharge chute 24. The position of the blank in the work holder may be adjusted so that the curved lip portion of the groove will be centered on the blank by adjusting the position of plate 64. Such adjustment moves the side support 67 and the lip support 70 so that the lip support and the side support remain in fixed relation to each other and the heel seat engaging plate 64 through the series of adjustments necessary to center the groove on the various sizes of blanks in any given order. Support for the edge of the shank lip is required only on that side of the lip at which the cutter cuts out through the seat surface of the blank. Unless supported very close to the cutter at this point the wood is frequently fractured and splintered to a damaging extent. The opposite side of the lip needs no close support because at that point the cutter is cutting on to the blank towards solid uncut wood. At the start of an order of blanks the operator adjusts lip support 70, if necessary, by loosening screw 73 so the cutter will just shave the end of the support at the end adjacent the side support 67 after which it is usually possible to groove all sizes without further attention to the lip support because the edge of the lip needing support maintains a nearly constant distance from the adjacent side of the blank, on all sizes.

Inasmuch as the width of the shank lips vary while the center thickness remains the same on the different sizes and as the groove must always meet the seat surface at the sides as shown in Fig. 5, it is evident that the curvature of the shank lip must vary with the sizes of heel. This is accomplished in the machine illustrated by changing the distance from the axis of the shaft 48 to the tool 21 forming the convex curvature of the shank. To this end the operator positions

70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

the work holder over the tool as shown in Fig. 2. He then locks the work holder beam 51 by clamping lug 100 between clamp jaws 103 and 104. When the work holder is thus locked it will be noted that the heel seat engaging surface of the plate 64 is perpendicular to a plane through the axes of rotation of the shaft 48 and the tool 21. He then loosens bolts 52 slightly so that the work holder assembly is slideable on its bracket 50. Bolt 42 is then loosened and the plate 35 may be moved at will as required to change the radius of oscillation of the work holder. Bolts 42 and 52 then are tightened to hold the parts in their adjusted position. The arm 97 carrying the clamping jaws 103 and 104 then is moved to its inoperative position. Consequently, the curvature of the shank is changed without changing the thickness of the lip at its center because the previous relation between the tool 21 and the heel seat engaging plate 64 is maintained.

Breast stop 30 determines the depth to which the tool cuts into the blank. Bolt 32 permits adjustment of this stop so that lip trimming cutters 23 just smooths the surface of the lip. The breast stop is adjustably fixed on the frame of the machine so that it acts only to position the blank for clamping. Thus, the breast stop is positioned at all times at the blank loading position of the work holder.

30 I claim:

1. In a heel blank breasting machine, in combination, a frame, a tool rotatably carried by said frame, a carrier movably mounted upon said frame, a heel blank holder mounted upon said carrier to permit movement parallel to a given plane and in operative relation to said tool, said heel blank holder including a heel blank seat surface engaging member and a heel blank side support arranged to prevent movement relative to one another in a direction parallel to said plane, and means permitting simultaneous adjustment of said member and support in a direction parallel to said plane, said holder also including a heel shank edge support carried by said member.

45 2. In a heel blank breasting machine, in combination, a frame, a tool rotatably carried by said frame, a heel breast stop secured upon said frame, a carrier movably mounted upon said frame, a heel blank holder mounted upon said carrier to permit movement parallel to a given plane from a position in operative relation to said breast stop past and in operative relation to said tool, said heel blank holder including a heel blank seat surface engaging member and a heel blank side support arranged to prevent movement relative to one another in a direction parallel to said plane, and means permitting simultaneous adjustment of said member and support in a direction parallel to said plane, said holder also including a heel shank edge support carried by said member.

60 3. In a heel blank breasting machine, in combination, a frame, a tool rotatably carried by said frame, a rotatable member mounted upon said frame, means permitting adjustment of said member in a direction parallel to a plane perpendicular to its axis of rotation, said axis of rotation being perpendicular to the axis of rotation of said tool, a heel blank holder adjustably carried by said member so that a heel blank carried by said holder may be moved in a plane parallel to the axis of rotation of said tool by said member past and in operative relation to said tool, and means for locking said holder in a given relation to said tool while the position of said member is adjusted

to change the position of its axis of rotation with relation to said holder.

4. In a heel blank breasting machine, in combination, a frame, a tool rotatably carried by said frame, a rotatable member mounted upon said frame, means permitting adjustment of said member in a direction parallel to a plane perpendicular to its axis of rotation, said axis of rotation being perpendicular to the axis of rotation of said tool, a heel blank holder adjustably carried by said member so that a heel blank carried by said holder may be moved in a plane parallel to the axis of rotation of said tool by said member past and in operative relation to said tool, means for locking said holder in a given relation to said tool while the position of said member is adjusted to change the position of its axis of rotation with relation to said holder, and a heel breast stop adjustably secured to said frame.

5. In a heel blank breasting machine, in combination, a frame, a tool rotatably carried by said frame, a rotatable member mounted upon said frame, means permitting adjustment of said member in a direction parallel to a plane perpendicular to its axis of rotation, said axis of rotation being perpendicular to the axis of rotation of said tool, a heel blank holder adjustably carried by said member so that a heel blank carried by said holder may be moved in a plane parallel to the axis of rotation of said tool by said member past and in operative relation to said tool, and means for locking said holder in a given relation to said tool while the position of said member is adjusted to change the position of its axis of rotation with relation to said holder, said blank holder including a heel blank seat surface engaging member and a heel blank side support arranged to prevent movement relative to one another in a direction parallel to said plane while permitting simultaneous adjustment of said member and support in a direction parallel to said plane and perpendicular to the direction of said change in position of the axis of rotation of said member.

6. In a heel blank breasting machine, in combination, a frame, a tool rotatably carried by said frame, a rotatable member mounted upon said frame, means permitting adjustment of said member in a direction parallel to a plane perpendicular to its axis of rotation, said axis of rotation being perpendicular to the axis of rotation of said tool, a heel blank holder adjustably carried by said member so that a heel blank carried by said holder may be moved in a plane parallel to the axis of rotation of said tool by said member past and in operative relation to said tool, means for locking said holder in a given relation to said tool while the position of said member is adjusted to change the position of its axis of rotation with relation to said holder, said blank holder including a heel blank seat surface engaging member and a heel blank side support arranged to prevent movement relative to one another in a direction parallel to said plane while permitting simultaneous adjustment of said member and support in a direction parallel to said plane and perpendicular to the direction of said change in position of the axis of rotation of said member, a heel breast stop secured to said frame, and means for adjusting the positions of said member and support relative to said stop in a direction perpendicular to said plane.

7. In a heel blank breasting machine, in combination, a frame, a tool rotatably carried by said frame, a movable carrier adjustably mounted

upon said frame, a heel blank holder adjustably mounted upon said carrier so as to be moved in an arcuate path past said tool to bring a heel blank carried by said holder in operative relation 5 to said tool, and means for locking said blank holder in a given relation to said tool while the position of said carrier is adjusted on said frame to change the curvature of the arcuate path travelled by said holder.

10. 8. In a heel blank breeding machine, in combination, a frame, a tool rotatably carried by said frame, a rotatable member mounted upon said frame, means permitting adjustment of the axis of rotation of said member along a line formed 15 by the intersection of a plane through its axis of rotation and the axis of rotation of said tool with a plane parallel to the axis of said tool and perpendicular to the axis of rotation of said member, a heel blank holder adjustably carried by said member so that a heel blank carried by said holder may be moved in a plane parallel to the 20 axis of rotation of said tool by said member past and in operative relation to said tool, and means for locking said holder in a given relation to said 25 tool while the position of the axis of rotation of said member is adjusted along said line.

9. In a heel blank breeding machine, in combination, a frame, a tool rotatably carried by said frame, a rotatable member mounted upon said frame, means permitting adjustment of the axis of rotation of said member along a line formed 30 by the intersection of a plane through its axis of rotation and the axis of rotation of said tool with a plane parallel to the axis of said tool and perpendicular to the axis of rotation of said member, a heel blank holder adjustably carried by said member so that a heel blank carried by said holder may be moved in a plane parallel to the 35 axis of rotation of said tool by said member past and in operative relation to said tool, said holder having a heel blank seat engaging surface adapted 40 to be positioned perpendicular to a plane through the axes of rotation of said member and said tool, and means for locking said holder with

its heel blank seat engaging surface in said perpendicular position.

10. In a heel blank breeding machine, in combination, a breeding tool, a blank holder rotatable to swing said holder past said tool, said holder comprising a combined seat surface clamping jaw and blank side support, said combined jaw and support being adjustable as a unit crosswise of the holder, and a toplift surface clamping jaw. 5

11. In a heel blank breeding machine, in combination, a breeding tool, a blank holder rotatable to swing said holder past said tool, said holder comprising a combined seat surface clamping jaw and blank side support, said combined jaw and support being adjustable as a unit crosswise 15 of the holder, a toplift surface clamping jaw, and a fixed blank breast stop. 10

12. In a heel blank breeding machine, in combination, a breeding tool, a blank holder movable to carry said holder past the tool, said holder comprising a combined unitary heel seat surface clamping jaw and blank side support, a removable shank lip edge support carried by said jaw, and a toplift surface clamping jaw. 20

13. In a heel blank breeding machine, in combination, a breeding tool, a blank holder movable to carry said holder past the tool, said holder comprising a combined unitary heel seat surface clamping jaw and blank side support, a removable shank lip edge support carried by said jaw, 25 said combined jaw, side support and shank lip support being adjustable as a unit, crosswise of the holder, and a toplift surface clamping jaw. 30

14. In a heel blank breeding machine, in combination, a breeding tool, a blank holder movable 35 to carry said holder past the tool, said holder comprising a combined unitary heel seat surface clamping jaw and blank side support, a removable shank lip edge support carried by said jaw, said combined jaw, side support and shank lip 40 support being adjustable as a unit, crosswise of the holder, a toplift surface clamping jaw, and a fixed breast stop. 45

GEORGE T. WATT.
